UNITED STATES PATENT OFFICE.

ANTONIN CHAPAL, OF NEW YORK, N. Y.

MACHINE FOR CARROTING FURS.

No. 839,550.

Specification of Letters Patent.

Patented Dec. 25, 1906.

Application filed April 7, 1906. Serial No. 310,527.

To all whom it may concern:

Be it known that I, ANTONIN CHAPAL, a citizen of the United States, residing in the borough of Brooklyn, in the county of Kings, 5 in the city and State of New York, have invented certain new and useful Improvements in Machines for Carrotting Furs, of which the following is a specification.

This invention, as its title indicates, relates to a machine for carrottting fur to be used in hat-making; and the object of the invention is to provide a simple and inexpensive machine which combines handwork with machine-work—that is to say, the skin will 10 be held and manipulated by hand, while the machine automatically supplies and applies the carrottting liquid to the fur thereon. Means are provided for supplying the liquid as needed for regulating the depth the brush-fiber dips 15 into the liquid and for regulating the overflow of the liquid.

In the accompanying drawings, which illustrate an embodiment of the invention, Figure 1 is a front elevation of the machine. 20 Fig. 2 is a plan of the same. Fig. 3 is an end elevation of the same. Fig. 4 is a vertical transverse section taken in the plane indicated by line x^x in Fig. 1.

1 designates an open frame provided with 25 legs 2, and in this frame is rotatively mounted a cylindrical brush 3, the brush portion of which should be of a vegetable fiber. On the projecting journal 4 of the rotating brush are pulleys 5, through which the brush is 30 driven from a pulley 6 on a counter-shaft 7 above, with the aid of a belt 8. The brush rotates in the direction of the arrow z in Fig. 3.

Mounted in the frame is a tank or receptacle 9 to contain the carrottting liquid, (L in Fig. 4,) into which the fibrous portion of the brush dips slightly. The receptacle 9 is 40 made adjustable up and down by means of four screws 10 screwing through nuts 11 in the frame and having seats at their upper 45 ends in socket-plates 12, secured to the under side of the receptacle. By means of these screws the receptacle may be leveled up or tilted; as desired, and also be adjusted up and down to determine the depth of immersion of the tips of the brush-fiber in the liquid. The liquid is supplied to the tank 9 from a suitable reservoir 13 of any kind in 50 quantity as desired.

Mounted on the frame 1 at the back is an 55 inclined splash-board 14, having a hood formed of a top board 15 and side boards 16.

On the frame in front is an inclined shield 17, which extends upwardly over the front part of the brush and protects the workman in a good degree from the acidulated liquid 60 used. The liquid which may accumulate on the under side of this shield will flow back into the tank 9, as will also that thrown upon the splash-board 14.

The operation will be as follows: The machine having been set in operation and the proper amount of liquid supplied to the tank 9, the workman applies the skin to the brush with the fur down, being careful to shift it about in a manner to bring all the 65 fur in contact with the brush and to press it down with his fingers in order to exert the desired pressure as the work proceeds. As the fur on the skins is thus treated the latter are laid by to thoroughly dry before the fur 70 is sheared off. The liquid will of course be gradually exhausted by its application to the fur, and this waste is supplied or made good from the reservoir, from which the liquid runs or trickles in small quantity. Should 75 the liquid flow in faster than it is used up, the quantity in the tank 9 can rise no higher than the overflow 18, from which it may be caught in any suitable receptacle and returned to the reservoir. 85

Heretofore, so far as known, when machines have been employed or proposed for carrottting furs the idea has been to effect the whole operation automatically—that is, to apply the fur (on the skin) to the brush automatically. This has not given good results, and the machines are relatively very expensive. I have found that some part of the work may be done automatically with 90 good results; but the application of the fur to the brush requires careful and skilled manipulation, which cannot be satisfactorily supplied by mechanism. 95

Having thus described my invention, I claim— 100

1. A machine for the purpose specified, having a frame, a rotating brush mounted in said frame, and exposed above so that the skin may be applied thereto, a tank under the brush to contain the carrottting liquid, and provided with an overflow-outlet, means for moving said tank up and down for regulating the extent of immersion of the brush, and means for supplying the liquid to the tank 105 gradually as it is used. 110

2. A machine for the purpose specified, having a frame, a brush rotatively mounted

in said frame, means for rotating said brush, a shield 17 in front of and extending up over the front of said brush, a hooded splash-board 14 on the frame back of the brush, four upright screws 10, mounted in the frame, a tank 9 to receive the carotting liquid and house the lower part of the brush, said tank having an overflow-outlet 18 and sockets 12 which receive the ends of the screws 10, and

means for supplying the liquid gradually to said tank.

In witness whereof I have hereunto signed my name, this 6th day of April, 1906, in the presence of two subscribing witnesses.

ANTONIN CHAPAL.
